Attorney

UNITED STATES PATENT OFFICE.

JAMES E. MEED, OF PALESTINE, WEST VIRGINIA.

DEPTH-GAGE FOR FILLISTER OR RABBET PLANES.

1,358,969.

Specification of Letters Patent. Patented Nov. 16, 1920.

Original application filed March 28, 1918, Serial No. 225,151. Divided and this application filed November 7, 1918, Serial No. 261,458. Renewed April 15, 1920. Serial No. 374,200.

To all whom it may concern:

Be it known that I, JAMES E. MEED, a citizen of the United States, residing at Palestine, in the county of Wirt and State 5 of West Virginia, have invented new and useful Improvements in Depth-Gages for Fillister or Rabbet Planes, of which the following is a specification.

This invention relates to a depth gage for 10 fillister or rabbet planes, the present application being a division of my prior application for adjustable fillister or rabbet planes, filed March 28, 1918, Serial No. 225,151.

The object of the invention is to provide 15 a convenient, reliable and efficient type of gage for regulating the depth of cut, which gage may be adjusted to vary its working position for any depth of cut and quickly removed when it is desired to make abnormally deep cuts or work close to a marginal surface.

The invention consists in the features of 20 construction, combination and arrangement of parts hereinafter fully described and claimed, reference being had to the accompanying drawing, in which:—

Figure 1 is a view in side elevation, looking 25 toward the right hand side of the plane, and showing my improved gage applied for use.

Fig. 2 is a vertical transverse section on line 2—2 of Fig. 1.

Fig. 3 is a similar view with the depth gage removed.

Referring to the drawing, 1 designates the 30 body or stock of the plane, including a bottom plate or shoe 2 and a continuous side plate 3, said side plate being shown in the present instance at the right hand side of the stock. The bottom plate is divided, as is 35 usual in planes of this character, to provide the throat 6, through which the cutting edge of the plane-iron or cutting-bit 7 projects.

A gage 67 is provided for limiting the 40 depth of the cut, and comprises a bar extending longitudinally upon the outer side of the side plate 3 and adjustable to different elevations to vary the depth limit of the cut to any desired extent. As shown, the bar 67 is 45 pivotally connected at its ends with the lower ends of a pair of swinging arms 68 having crank disks 69 at their upper ends, said crank disks being coupled by a connecting rod 70 holding the crank disks prop- 50 erly spaced. The arms 68 are made of

spring metal and have bowed lower ends, and the bar 67 is provided in alinement with said arms with studs 71 adapted for engagement with gage sockets or recesses 72 formed in the side plate 3. The sockets or recesses 60 extend on arcs concentric with the pivot members of the arms 60 and are arranged at different elevations, so that by engagement of the studs 71 under the spring action of the arm 68, with horizontally alined sockets 65 disposed at a desired elevation the bar will be spaced a determined distance from the surface of the bottom plate to limit the depth of the cut to the desired degree. On the face of the side plate 3 is provided a 70 suitable inch or other scale for indicating the degrees of adjustment to which the bar may be set, the divisions of which scale are in proper alinement with the sockets 72. The crank disks 69 of the arms 68 are 75 formed with threaded openings which engage reduced threaded stems 73 upon the outer ends of rotary shafts 74, which stems thus support and hold the disks 69 pressed against the face of plate 3. The shafts 74 80 are journaled in bearings 75 on the plate 3 and are provided at their inner ends with actuating knobs or heads 76. At the intersection of the shaft 74 with the reduced stem 73 shoulders are formed against which bear 85 washers or abutment disks 77 which are threaded on said stems and then punch-keyed or otherwise locked in engagement with the threads, which abutments are movable in counterbores or recesses 78 formed 90 in the bearings. A coiled spring 79 is interposed between each bearing and the knob or head 76 and normally acts upon and in cooperation with the stem 73 to hold the crank disk 69 forced against the face of the 95 plate 3, thus adapting the bowed free end of each arm 68 to have the desired spring locking action, while at the same time holding the gage members in close contact with the sides of the plate 3. It will be understood that by pulling outward on the arms 100 68 the studs 71 may be disengaged from the sockets they engage and the gage swung in one direction or the other to adjust the bar 67 to the desired elevation, and that as 105 said bar swings downwardly it also swings forwardly, while on the upward movement of the bar it will also swing rearwardly, the construction being such that when the bar reaches the desired elevation the studs will 110

snap into the sockets registering therewith and hold it in position until forcibly displaced by positive manipulation by the operator. By turning the knobs 74 in the proper direction to unscrew the stem 73 from the crank disks 69 the arms 68 will be disengaged therefrom, whereby the gage may be detached whenever desired from the tool. When the arms 68 are so released from the shafts 74 the latter will be forced inwardly by the springs 79 so that the stems 73 and abutments 77 will be housed and concealed entirely within the recesses 78, thus leaving the outer face of the side plate 3 free from projections so that it may slide freely in contact with the work or other object in certain operations of the tool. The function of the rod 70 is to hold the disks 69 accurately spaced apart and in proper relationship while the shafts 74 are being manipulated to connect the stems 73 with said disks.

Having thus fully described my invention, I claim:—

1. The combination with a plane comprising a stock having a side plate, the said plate having arcuate series of sockets therein, of spring arms pivoted at their upper ends upon said plate and having their lower end bowed, forming spring members adapted to pass over said series of sockets, the said upper ends of the arms being provided with crank members, a gage bar carried by the bowed free ends of said arms, studs upon said gage bar adapted to interlock with said sockets, and a rod connecting the crank members of the said spring arms.

2. The combination with a plane having a stock provided with a side plate, of rock shafts mounted upon said plate, swinging arms having crank elements and connected with the rock shafts, said arms having

bowed portions forming spring members, a gage bar pivotally connected with the bowed portions of the swinging arms, a casing between the crank elements of the swinging arms, interlocking means upon the bar and side plate adapted for engagement under pressure of the spring members of the swinging arms, and springs acting upon the rock shafts for normally holding the swinging arms under tension. 45

3. A fillister or rabbet plane comprising a stock having a side plate, rock shafts slidably and rotatably mounted upon said plate, swinging arms having crank elements detachably connected with the rock shafts, said arms having bowed portions forming spring members, a gage bar pivotally connected with the bowed portions of the swinging arms, a connection between the crank elements of the swinging arms, interlocking means upon the bar and side plate adapted for engagement under the pressure of the spring members of the swinging arms, and springs acting upon the rock shafts for normally holding the swinging arms under tension and adapted upon the disengagement of said swinging arms from the rock shafts, to slide the shafts inwardly beyond the face of 70 the side plate. 60

4. In a device of the class described, a plane comprising a stock having a side plate provided with spaced recesses, threaded stems rotatably mounted in said recesses, 75 gage arms detachably connected to said stems at one end thereof, a gage bar connecting the said arms, a spring for each of said threaded stems tending to force the same inwardly from the outer surface of said side plate, and means for limiting the movement of said stems. 80

In testimony whereof I affix my signature.
JAMES E. MEED.
